UNITED STATES PATENT OFFICE.

NICHOLAS SCHOLL, OF CHILLICOTHE, OHIO.

IRONING-STAND.

SPECIFICATION forming part of Letters Patent No. 272,906, dated February 27, 1883.

Application filed December 30, 1882. (No model.)

To all whom it may concern:

Be it known that I, NICHOLAS SCHOLL, a citizen of the United States, residing at Chillicothe, in the county of Ross and State of Ohio, have invented a new and useful Ironing-Stand, of which the following is a specification, reference being had to the accompanying drawings.

This invention relates to ironing-tables; and it consists in certain improvements in the construction of the same, which will be hereinafter fully described, and particularly pointed out in the claims.

In the drawings hereto annexed, Figure 1 is a perspective view of my improved ironing-board extended and ready for operation. Fig. 2 is a perspective view, showing the board detached and the frame folded for transportation or storage. Fig. 3 is a longitudinal vertical sectional view of the table extended for operation, and Fig. 4 is a rear view.

The same letters refer to the same parts in all the figures.

A in the drawings refers to an upright mounted upon a cross-piece, B, which forms the support of the device. To the front side of said upright, near its upper end, is hinged a bar, C, having at its outer end a cross-piece, D, adapted to rest upon the floor and form the other support of the device.

30 E is a block having a band, F, encircling the bar C, upon which the said block may slide. To secure it in any position to which it may be adjusted, the said block is provided with a vertical perforation, G, in which moves a pin, H, adapted to enter any one of a series of perforations, I I, in the bar C. The pin or plug H is forced downwardly by means of a suitably-arranged spring, J, which, as in the drawings, may consist of an ordinary rubber strap 35 passed through a transverse perforation near the head of the pin H, and having its ends secured to the sides of the block E. By this spring the accidental withdrawal of the pin H is prevented.

40 To the upper end of the upright A is hinged a frame, K, consisting, essentially, of side pieces, L L, which may be connected and spaced by one or more cross-pieces, M. The frame K may be hinged in position by means of a bolt, N, 45 passing transversely through its side pieces, as shown.

O O are segmental brackets, hinged to the sides of frame K by another transverse bolt, P, and said brackets are provided with notches Q Q, adapted to engage hooks R upon the sides 55 of the upright A, and thereby sustain the frame K in any position to which it may be adjusted.

S is the ironing-board, which is provided on its under side with a transverse cleat, T, having recesses U U, to receive the front ends of 60 the side pieces, L, of the frame K. At its rear end the board S is provided with a downwardly-projecting bolt, V, having a swiveled clamp, W, adapted to be adjusted under the side pieces of the frame K, and tightened up 65 against the latter by a thumb-nut, X, thereby serving to hold the board S securely in position upon the frame. The board S is provided on its upper side with a staple, Y, adapted to receive the lower end of a sleeve-board, Z, which latter is also provided with legs A² A², adapted 70 to enter sockets B² in the face of board S, and thereby sustain the sleeve-board in an inclined position, as shown in the drawings. Upon the under side of board S, near its edge, is a series 75 of staples, C² C², through which the cord D², by which the cloth E² is secured upon the board, is threaded. In this manner the cloth may be more conveniently and durably attached than by crossing the cord under the 80 board, as is now commonly done.

The sliding block E of the main frame has a transverse perforation, F², in which is pivoted a bail, G², the ends of the arms of which are bent or hooked and hinged in staples H² upon the rear side of the standard or upright A.

The operation of this invention will be readily understood from the foregoing description, taken in connection with the drawings hereto annexed.

The height of the table may be regulated by properly adjusting the upright A and bar C in relation to each other, which may be done by means of the sliding block E.

When the device has been adjusted to the proper height, the ironing-board and its supporting-frame may be adjusted to a horizontal position and retained in the same by means of the segmental brackets O, engaging the hooks R.

The sleeve-board, when not in actual use, may be easily detached from the main ironing-board;

but when it is to be used it is placed in the position shown, and brought to a horizontal position by lowering the front end of the main ironing-board S.

5 When the device is not in use, the board S may be detached from the supporting-frame, and the latter folded, as shown in Fig. 2, for storage or transportation.

I claim as my invention and desire to secure

by Letters Patent of the United States—

1. In an adjustable ironing-stand, the combination of the upright or standard, the bar or brace hinged to the same, and provided with a series of perforations, the block sliding upon 15 said hinged bar, and having a pin forced downwardly by a spring so as to engage said perforations, and a bail pivoted in a transverse perforation in said sliding block, and having the ends of its arms hinged to the upright or 20 standard, substantially as set forth.

2. In an adjustable ironing-stand, the herein-described frame, consisting of an upright, a hinged brace, a block sliding upon said brace,

and connected with the standard by a pivoted bail, and a frame hinged to the upper end of 25 the standard, and having hinged segmental brackets provided with notches engaging hooks upon the sides of the standard, in combination with a detachable ironing-board, substantially as set forth. 30

3. The combination, with the herein-described stand having hinged frame K, of the ironing-board S, having transverse cleat T, provided with recesses U U, and the bolt V, having swiveled clamp W and thumb nut X, as set 35 forth.

In testimony that I claim the foregoing as my own I have hereto affixed my signature in presence of two witnesses.

NICHOLAS SCHOLL.
